UNITED STATES PATENT OFFICE.

CHARLES E. BURNAP, OF CHICAGO, ILLINOIS, ASSIGNOR TO CYRUS BURNAP, OF NARBERTH, PENNSYLVANIA.

BOILER.

1,119,063.

Specification of Letters Patent.

Patented Dec. 1, 1914.

Application filed July 20, 1904, Serial No. 917,329. Renewed April 24, 1914. Serial No. 834,218.

To all whom it may concern:

Be it known that I, CHARLES E. BURNAP, a citizen of the United States, residing at Chicago, in the county of Cook and State 5 of Illinois, have invented certain new and useful Improvements in Boilers, of which the following is a specification.

My invention is concerned with a novel boiler designed primarily for use in solar 10 motors, but which, of course, may be used elsewhere.

In applying my invention, I utilize the principle of the ordinary steam engine, but instead of using water, I preferably employ 15 some other liquid, such as anhydrous ammonia, whose boiling point is very much below that of water, and for the boiler I employ a structure having a very small capacity compared with its area which is exposed to the source of heat, by which the 20 temperature of the inclosed liquid is raised to the vaporizing point against the pressure to which it is subjected in the boiler, which of course must have the necessary strength 25 to withstand this pressure.

To illustrate my invention, I annex here- 30 to four sheets of drawings, in which the same reference characters are used to designate identical parts in all the figures, of which,—

Figure 1 is a side elevation of my apparatus as utilized for pumping purposes, and employing a closed or submerged condenser; Fig. 2 is a view of the boiler looking 35 at it at right angles to the surface which is exposed to the sun; Fig. 3 is a cross section through a portion of the boiler on the line A—A of Fig. 6; Fig. 4 is a view of the portion of the boiler shown in the upper 40 left-hand corner of Fig. 2, but on an enlarged scale and with a portion of it in section to show some of the interior construction; Fig. 5 is a sectional view of the same on the line B—B of Fig. 4; Fig. 6 is an end 45 elevation of one of the header sections; Fig. 7 is a side elevation of one of the same; Fig. 8 is a sectional view similar to Fig. 3, but showing a modification of the boiler construction; Fig. 9 is a sectional view of the 50 same on the line C—C of Fig. 8; Figs. 10 and 11 are sectional views of the corrugated plates for making the boiler tubes, as they are shown in Figs. 3 and 8, but illustrat-

ing modifications; Fig. 12 is a cross section illustrating still another method of forming the boiler tubes; and Fig. 13 is a cross section illustrating still another method of forming the same.

Referring now to Fig. 1, 30 represents the boiler, which for the present I will simply 55 describe as of a generally rectangular shape and having its upper surface adapted to be set at whatever angle is most suitable to receive the rays of heat most nearly at right angles. The upper end of the boiler is connected by the elbow 31 with the pipe 32, in which is preferably placed the stop cock 33 for closing the upper end of the boiler when desired. Beyond the cock 33 the pipe 32 enters the separator 34, which may be of 60 any desired construction, and like the separators for steam, is adapted to catch any of the liquefied vapor and prevent it passing to the engine. The separator 34 is connected at its lower end by the pipe 35 with 65 the reservoir 36, which is preferably an elongated cylinder extending just beneath the upper end of the boiler, and serving to keep the liquid in the system at a level which shall be near the top of the boiler. 70 Extending down from the bottom of the reservoir 36 is a pipe 37, which is connected by the T-shaped union 38 with the returning pipe 39 which leads to the bottom of the boiler, it being connected to the headers at 75 the lower end thereof by the elbow 40. The union 38 has a three-way cock 41 therein, and is also adapted to have the supply cylinder 42 (shown in dotted lines,) screwed into the end when it is desired to add an 80 extra supply to the system as the anhydrous ammonia, or other liquid employed, becomes lowered by the unavoidable waste. In ordinary use, the three-way cock 41 is set so that only the pipes 37 and 39 are in 85 communication, but when the supply is to be replenished, the cylinder 42, with its valve 43 closed, is screwed into the end of the union 38, and its valve 43 opened, and the cock 41 turned so that the pipes 37 and 90 39 will be in communication with the cylinder 42. The vaporized fluid passes over the separator 34, down the pipe 44, whose valve 45 will be opened, and into the engine 95 valve chest 46, which is of the customary 100 construction.

The piston rod (not shown) is extended to the right, and where the apparatus is to be used for pumping water, as shown in the present illustration, carries at its right-hand end the piston (not shown) of the pump 53, which may be of any customary construction, and draws the water from the supply pipe 54 through the pump, and out the discharge pipe 55, which opens into the lower end of the cylindrical closed condenser 56, through which the water passes and is delivered from the upper end thereof through the pipe 57 to any point where it is to be utilized. This condenser 56 contains the worm 58, whose upper end is connected by the pipes 59 and 60 with the exhaust of the engine, and whose lower end is connected by the pipe 61 with the circulating pump 62, which has its cylinder preferably formed as an extension of the adjacent head of the engine cylinder, and whose piston is formed on the left-hand end of the piston rod, which is extended to the left for that purpose. The piston in the pump barrel 62 operates to draw a fresh supply of the condensed ammonia from the worm, and to force it down into the pipe 72, which is connected by the T-shaped union 73 with the return pipe 39 of the system.

From a consideration of the structure previously described, it will be apparent that the liquid anhydrous ammonia is held in the boiler 30 in a liquid form under the considerable pressure which is needed to keep it liquefied at the condenser temperature. As the liquid rises in the boiler, it is vaporized by the additional heat received, and passes into the engine, where it gives up some of its energy in operating the engine, and it passes from the exhaust into the condenser, where it is liquefied, and from whence it is pumped back into the boiler, against the pressure thereof, this being easily accomplished on account of the small area of the piston of the bottom 62 relative to the piston of the engine 46.

As will be seen from Figs. 2 to 7, the boiler 30 is constructed of a plurality of longitudinal sections, so that a boiler of any desired area may be obtained by bringing together the required number of sections. Each section has at its lower end a header 74 and at its upper end a similar header 75, the two sets of headers being identical in design except that the upper ones are of somewhat greater diameter in order to furnish the necessary space for the vaporized liquid. In Figs. 3 to 7 are illustrated the details of the upper headers, and it will be seen that each one consists of the elongated tubular body portion 76 having the downwardly-projecting flange 77 terminating in the shoulder 78, which furnishes a seat for the bottom of the trough 79, which is preferably of wood, and of a shallow construction, as shown.

The tubular bodies 76 of the headers terminate in the ears 80 and 81, which have suitable apertures through which pass bolts to fasten the adjacent sections securely together. The headers at the left-hand end 70 have in their enlarged ends the annular channel 82, and at their other ends have corresponding annular projections similar to the annular projection 83 shown in Fig. 4, on the cap 84 closing the outer end of the sections. The general outline of the interior of the header bodies is circular, as shown in Figs. 5 and 6, but this cylindrical interior is separated into two parts throughout practically the entire length by means of the web 85, the larger channel 86 serving to hold the bulk of the liquid and permitting it to pass freely to each of the sections, while the smaller upper channel 87 communicates directly with the ends of the boiler tubes, and the casting constituting the header has this channel 87 opening throughout practically its entire length by means of the aperture 88, into the plain face 89 constituting that side of the header. The aperture 88 is slightly wider than the bottom portion of the channel 87, which has a still wider central portion 90, which in connection with the reduced portion surrounding the aperture 88, forms the shoulders 91, which 95 serve to hold the boiler tubes in place, as will be subsequently described. The shallow trough 79 is, as stated, preferably made of wood, and has its bottom lined with one or more layers 92 of tarred paper or some similar moisture-proof material. On this paper is placed a layer 93 of sawdust, or some similar cheap non-conducting material, and upon this is placed still another layer 94 of tarred paper, and on this are placed the 105 boiler tubes, the object of the use of the heat-retaining material of course being to prevent any unnecessary conduction of heat from the apparatus. The boiler tubes are especially designed to have a small liquid 110 capacity, together with a large area subject to the heat, and to be sufficiently strong to resist the pressure, and at the same time of a structure that can be manufactured cheaply. A preferred method of constructing these is to employ two layers 95 and 96 of thin sheet-metal, which are first corrugated, the corrugations of the layer 95 not being quite so deep as those of the layer 96, then nested together, and finally compressed 115 in a plane so as to bring the corrugations closer together and to bend them into the double-loop shape clearly shown in cross section in Fig. 3. When they are bent in this shape and sufficiently compressed, the larger 120 and smaller loops are filled by a cement or other packing 97, which can be applied in a liquid form when cement is used, and which when solidified serves to hold the boiler tubes thus formed rigidly in their po- 130

sition and so securely that they cannot be displaced or blown out. At the ends the plates are folded together, as shown at 98, and the making of a liquid-tight joint may 5 be further assisted by the employment of a layer of solder, as shown at 99. The interior surfaces of these boiler tubes are preferably plated with tin, or some similar metal, to close any pores that might be in 10 the surface of the steel. The tubes are slightly thickened at the ends, as shown at 100, by soldering on a strip of metal or by electro-deposition, the object of the thickening being to form a shoulder which shall 15 operate with the shoulder 91, as clearly shown in the sectional parts of Figs. 4 and 5, to prevent the tubes from drawing out of the headers. The tubes are preferably 20 coated with a heat retaining paint having some form of carbon as a basis. Above the surface of the boiler tubes is a dead-air space 101, the dead-air space 101 being formed by securing a sheet 102 of some diathermanous material, such as glass, at a 25 suitable distance above the tubes, and conveniently by resting its edges on the shoulders 103 formed on the sides of the trough and the shoulders 104 formed on the headers, and by clamping the sheet 102 down on 30 these shoulders by means of the overlapping metallic strip 105, secured in position by screws, as shown in Fig. 5.

The different sections of the boiler are assembled side by side and clamped together 35 by the tie rods 106, which pass through the troughs beneath the tubes, and preferably through one flange of the angle-irons 107, preferably placed at the sides of the boiler. The glass sheets 102 may be long enough 40 to extend entirely across the boiler, as shown at the right hand of Fig. 2, or they may be made of a plurality of sheets made to overlap, as shown in the central part of said figure, or they may be made of a plurality 45 of sheets brought together on sashes 108, as shown at the left-hand portion of said figure. By this construction, it will be seen that I have produced a very simple, and yet substantially and cheaply constructed 50 boiler, which secures the large heating surface with the small interior area which is essential for this class of devices.

Referring now to Figs. 8 to 13, I have 55 illustrated modifications of the boiler structure which has just been described. In Figs. 8 and 9, I have shown a modification in which the headers do not have the web 85, and in which the additional strength required by its absence is secured by the use 60 of the eccentric annular ribs 109, which, as will be clearly seen, give an additional rigidity and strength to the header sections and prevent any possibility of the vapor pressure applied at the edges of the recess ad-

mitting the boiler tubes from splitting the 65 headers. In this construction, I preferably make the trough 110 of sheet-metal, instead of wood, as illustrated in the other form, and the two corrugated layers of sheet steel are secured together by soldering them 70 at the bottoms of the ribs. To effect this result, I will place strips of solder in the corrugations of the lower sheet 111, then apply the upper sheet 112 thereto, and then holding the sheets together firmly with weights, 75 I will apply sufficient heat to the under surface to fuse the solder, and the weight forcing the upper sheet 112 down into the lower sheet 111 will insure the two sheets being soldered together with the utmost strength. 80 In Figs. 10 and 11, I have illustrated modifications of the structure shown in Figs. 8 and 9. In Fig. 10, the lower sheet 113 has twice as many corrugations as the upper sheet 114, and the interior cross sec- 85 tion of the tubes is varied as shown. In Fig. 11, the design of the lower sheet 115 and the upper sheet 116 is the same, but they are placed together with their concave surfaces facing each other, and are soldered 90 together at their contacting flat surfaces 117.

In Fig. 12, I illustrate a modification of the boiler first described and illustrated, in which the two corrugated sheets are em- 95 ployed, but in which the soldering is dis- pensed with and the sheets are lapped, as shown at 127, to secure them together. To form these tubes, the corrugated sheets are first pressed into shape on the forming sur- 100 face 128 shown at the right-hand of the figure. The folds are then bent at right angles, as shown in the central portion of said figure, this being effected by the use of rolls of any suitable design for this purpose. 105 Finally, the portions bent at right angles are folded completely on themselves by the use of a roller of special design, such as shown in section at 129, and in a manner that will be readily understood from an ex- 110 amination of the figure.

In Fig. 13, I illustrate still another method of forming the boiler sections, by using a pair of plates 130 and 131 having oppositely-disposed concave surfaces and 115 the contacting flat surfaces 132 which are secured together by electrically welding them, as indicated, by placing them between the poles 133 and 134.

In the illustration of the entire mecha- 120 nism, I have not endeavored to illustrate the supports, but have made the drawings diagrammatic, as it were, in order to more clearly illustrate the general system and connections employed.

While I have shown and described my in- 125 vention as embodied in the forms which I at present consider best adapted to carry

out its purposes, it will be understood that it is capable of modifications, and that I do not desire to be limited in the interpretation of the following claims except as may be necessitated by the state of the prior art.

What I claim as new, and desire to secure by Letters Patent of the United States, is,—

1. A boiler composed of two sheets of metal having interlapped corrugations, the corrugations of one sheet being shallower than those of the other for the purpose set forth, means for retaining said sheets rigidly in position, and headers at the top and bottom of said sheets for connecting the boiler tubes formed thereby.
2. A boiler composed of two sheets of metal having interlapped corrugations, the corrugations of one sheet being shallower than those of the other for the purpose set forth, headers at the top and bottom of said sheets for connecting the boiler tubes formed thereby, and a layer of filling material occupying the loops of said corrugations to hold the sheets rigidly in place.
3. A boiler section having the boiler tubes formed by the intermeshed corrugated sheets, substantially as described, the headers connecting the tops and bottoms of said tubes, and a layer of heat-retaining material, such as sawdust, upon which said tubes rest.
4. A boiler section having the boiler tubes formed by the corrugated sheets substantially as described, the headers connecting the tops and bottoms of said tubes, a layer of heat-retaining material, such as sawdust, upon which said tubes rest, and a layer of moisture-proof substance, such as tarred paper, interposed between the tubes and sawdust.
5. A boiler section composed of boiler tubes formed from intermeshed layers of corrugated metal, substantially as described, said tubes being mounted in a shallow trough having a layer of non-conducting

material, such as sawdust, therein, upon which the tubes rest.

6. A boiler section composed of boiler tubes formed from intermeshed layers of corrugated metal, substantially as described, 50 said tubes being mounted in a shallow trough having a layer of non-conducting material, such as sawdust, therein, surrounded by some moisture-proof substance, such as tarred paper, upon which the tubes rest. 55

7. A boiler section composed of boiler tubes formed by a pair of plates having intermeshed corrugations with thickened portions at their ends, and the headers having apertures in which said ends enter, said 60 apertures being provided with shoulders with which the thickened ends coöperate to prevent their withdrawal; substantially as and for the purpose described.

8. A boiler section composed of metallic 65 tubes having an extended surface and built up of intermeshed layers of corrugated metal, and an inclosed dead-air space above said extended surface, covered by a diathermanous material such as glass. 70

9. A boiler section composed of metallic tubes having an extended surface and built up of intermeshed layers of corrugated metal, an inclosed dead-air space above said extended surface, covered by a diathermanous material such as glass, and a layer of heat-retaining material, such as sawdust, beneath said tubes. 75

10. A boiler section composed of boiler tubes formed of two pieces of corrugated 80 sheet-metal fitted together so as to leave tubes crescent-shaped in cross-section between the plates and soldered together between said crescent-shaped tubes.

In witness whereof, I have hereunto set 85 my hand this 16th day of July, 1904.

CHARLES E. BURNAP.
